US0D1052014S

(12) **United States Design Patent** (10) **Patent No.:** **US D1,052,014 S**
(45) **Date of Patent:** **** Nov. 19, 2024**

(54) **DUMBBELL**

(71) Applicant: **Zhejiang TingJing Intelligent Technology Co., Ltd.**, Zhejiang (CN)

(72) Inventor: **Changsheng Fu**, Zhejiang (CN)

(**) Term: **15 Years**

(21) Appl. No.: **29/949,836**

(22) Filed: **Jun. 28, 2024**

(30) **Foreign Application Priority Data**

Apr. 28, 2024 (CN) 202430246538.5

(51) **LOC (14) Cl.** **21-02**

(52) **U.S. Cl.** ..... **USPC D21/681**

(58) **Field of Classification Search**

USPC D6/552; D21/662, 667-682, 685, 686, D21/692, 694
CPC A63B 2220/12; A63B 21/062; A63B 2220/13; A63B 69/3632; A63B 21/075; A63B 21/063; A63B 21/0628; A63B 21/0724

See application file for complete search history.

(57) **CLAIM**

The ornamental design for a dumbbell as shown and described.

DESCRIPTION

FIG. 1 is a perspective view of a dumbbell showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof

FIG. 9 is a partial enlarged view of portion 9 in FIG. 1; and, FIG. 10 is a partial enlarged view of portion 10 in FIG. 1. The dot-dash broken lines in FIGS. 1, 9, and 10 illustrate the border of partial enlarged detailed views and form no part of the claimed design.

1 Claim, 10 Drawing Sheets
